WILLIAM E. BRACEY AND LYFUS W. BRAMBLETT, OF DALLAS, TEXAS

COMBINATION TUBE AND BRUSH HOLDER

Application filed February 18, 1928. Serial No. 255,365.

This invention relates to new and useful improvements in combination tube and brush holders.

One object of the invention is to provide a holder for collapsible tubes and provided with a self-closing cap for sealing the tube, whereby it is not necessary to screw on the usual cap.

Another object of the invention is to provide a tube holder equipped with a cap operating means and a support for the tube so located that the tube may be squeezed and the cap operating means manipulated with the same hand, whereby the other hand is free to hold the tooth brush.

Another feature of the invention resides in a spring clamp for retaining the collapsible tube in position in the holder.

A construction designed to carry out the invention will be hereinafter described, together with other features of the invention.

The invention will be more readily understood from a reading of the following specification and by reference to the accompanying drawings, in which an example of the invention is shown and wherein:

Fig. 1 is a front elevation of a device constructed in accordance with our invention,

Fig. 2 is a plan view of the same showing a tube in place in the holder,

Fig. 3 is an end elevation,

Fig. 4 is a transverse sectional view taken on the line 4—4 of Fig. 1, and

Fig. 5 is a detail of the modified form of cap.

In the drawings the numeral 10 designates a supporting bracket having an arm 11 bent at substantially right angles thereto for mounting the bracket on a wall or other suitable place as by screws 12 or other means. The arm is provided with an outwardly directed flange 13 formed with keyhole slots 14 for receiving tooth brushes. A horizontal table or shelf 15 is suitably fastened at one end to a horizontal plate 16 attached to the upper edge of the bracket. The particular manner of connecting the table and the bracket is immaterial.

To hold in place a tube A, a spring clamp is provided and this clamp includes a vertical

fixed bar 17 and a vertical pivoted bar 18 which constitutes a lever. The bar 18 is pivoted to the outer face of the bracket 10 on a stud 19. The bars project above the table and below the bracket and the bar 17 has a fixed jaw 20 at its top, while the bar 18 has a movable jaw 21 at its top, said jaws being complementary. The jaws are dished and each has a notch 22. The dished portions of the jaws receive the crowned head B of the tube A, while the neck C is received in said notches, whereby the tube is clamped in place.

The bar or lever 18 has a lug 23 bent therefrom and supporting one end of a coiled spring 24, which is disposed on the inside of the bracket 10 and has its opposite end attached to an ear 25 carried by said bracket. The function of this spring is to hold the jaws in clamping relation about the neck C, said spring being located above the pivot 19. The bars 17 and 18 projecting below the bracket have their lower ends rounded and provide grips so that the operator may grasp the same and by swinging the lower end of the lever 18 inwardly, the jaw 21 at its upper end is swung from the jaw 20, said jaws thus being opened to release or receive the neck C of the tube. By this simple mechanism the tube may be easily and quickly placed in position or removed as may be desired.

One of the features of the invention is a self-closing cap and in carrying this out a bar 26 is directed downwardly from the central portion of the table 15, preferably from one end of the plate 16, as is illustrated. The bar constitutes a hanger and a lever 27 is pivoted on the lower end of the bar by means of a stud 28. A coiled spring 29 has one end attached to the upper portion of the hanger, while its opposite end is connected to the lever between the hanger and the bracket. This lever is twisted and bent at substantially right-angles to provide an upright arm 30. The lever is located so as to extend between the bars 17 and 18 below the bracket 10.

On the upper end of the arm 30 we provide a cap 31 having a pad 32 mounted therein. The pad is somewhat larger than the neck C of the tube and is made of cork or any other material suitable for the purpose of forming

an effective seal and closure when brought into engagement with the neck C of the tube. This cap may be rigidly mounted on the arm, as is shown in Figs. 1 and 2, or a pivoted cap 33 may be mounted on the upper end of the arm 30, as is shown in Fig. 5. This cap has a pad 34 in one end. The cap being pivoted, will more readily aline the face of its pad with the end of the neck C. The lever 27 is also twisted at 35 and bent at substantially right-angles to form a flat handle 36 underlying the table 15. By swinging the handle 36 upwardly the arm 30 will be swung outwardly and downwardly, as is shown in dotted lines in Fig. 1. This will remove the cap and pad from the neck of the tube, thus opening the same.

It is obvious that tooth brushes may either be supported in the slots 14 of the shelf 13 or at some other place, the shelf not being an essential feature of the invention, but greatly adding to the convenience of the device.

In using the device, the operator places the tube A on the shelf 15. This tube may contain tooth paste, or where the device is not used in connection with a tooth brush, but for some other purpose, it is obvious that any collapsible tube may be placed on the table 15. It will be assumed that the tube A contains tooth paste. The operator grasps the lower ends of the bars 17 and 18 and swings the bar 18 to open the jaws 20 and 21, as is shown in dotted lines in Fig. 4. The head B of the tube is moved into the dished portions of the jaws and the neck C is located in the notches 22. When the lever 18 is released, the spring 24, which has been tensioned, will swing the lever 18 inwardly, whereby the neck C will be clamped in said jaws.

Before inserting the tube in the device the usual screw cap is removed and discarded, and consequently when the neck C is inserted in the notches 22 its open end will come into contact with the pad 32 which will thus close the tube and take the place of the usual cap. Said pad, being made of cork, or other suitable material, will provide a tight closure.

When the operator desires to obtain paste from the tube, he places his hand around the tube and shelf, the latter being narrow, and grasps the handle 36. He is thus enabled to first swing the handle 36 upwardly, whereby the cap 31 is swung away, as is shown in Fig. 1, and the neck thus opened. He has then merely, while holding the handle in this position, to squeeze the tube A and thus eject tooth paste from the neck C, which may be caught upon the tooth brush held in the other hand. When he releases the handle 36 the spring 29 swings the arms 30 and the cap 31, thus closing the tube.

It is pointed out that the tube is held conveniently and firmly. It is advantageous to have the tube supported horizontally as this

enables the operator to readily observe the paste as it comes out of the neck, which is in full view, and the exact quantity desired may be more readily obtained.

Various changes in the size and shape of the different parts, as well as modifications and alterations, may be made within the scope of the appended claims.

What we claim, is:

1. In a tube holder, a bracket having a tube-supporting table and adapted to be rigidly mounted, whereby said table is supported in a horizontal position, automatically closing clamping jaws carried by the bracket in a vertical plane at one end of the table for receiving the neck of a tube mounted on said table, a lever pivotally supported intermediate its ends under the table and having a handle underlying said table, an arm carried by the lever, and a cap mounted on the arm in position for engaging the end of the neck of the tube.

2. In a tube holder, a rigidly mounted support having an elongated member for contact with the body of a collapsible tube, automatically closing jaws for engaging and clamping the neck of said tube at one end of said member, and a tube closure device including a lever pivotally mounted on the support under spring tension and carrying at one end a closure cap and an operating handle at the opposite side of the lever pivot from the cap and disposed substantially parallel to said elongated member for movement toward the same when the cap is withdrawn.

3. In a tube holder, a rigidly mounted support having a member contacting with the body of a collapsible tube, a fixed clamping jaw mounted upon the support at one end of said member, a cooperating pivoted jaw having an operating handle, a spring extending from said pivoted jaw to the support, a lever mounted on said support and carrying a cap to engage the neck of a tube, and an operating handle for said lever at the opposite side of its pivot from the cap and movable toward the tube supporting member when the cap is withdrawn.

4. In a tube holder, a tube support adapted to be rigidly mounted and having a face for supporting the body of a collapsible tube, a lever pivoted on the support at its face opposite the tube supporting face and having a cap mounted at one end thereof for engaging the end of the tube, resilient means carried by the support and engaged with the lever for holding the cap in contact with the end of the tube, and an operating handle from said lever disposed to move toward said body and substantially parallel to the tube supporting face when the cap is disengaged from the end of the tube.

5. In a tube holder, a bracket having a tube-supporting table and adapted to be rig-

idly mounted, automatically closing clamping jaws carried by the bracket at one end of the table for receiving the neck of a tube mounted on the table, a lever pivotally supported from the table intermediate its ends and having a handle disposed to swing toward and from said table, an arm carried by the lever, and a cap mounted on the arm in position for engaging the end of the neck of the tube.

10 In testimony whereof we affix our signatures.

WILLIAM E. BRACEY.
